UNITED STATES PATENT OFFICE.

ELIAS OLIVER PEALER, OF SAYRE, PENNSYLVANIA.

DESIGN FOR A SPOON-BAIT.

SPECIFICATION forming part of Design No. 24,724, dated October 1, 1895.

Application filed June 4, 1894. Serial No. 513,480. Term of patent 14 years.

To all whom it may concern:

Be it known that I, ELIAS OLIVER PEALER, a citizen of the United States, residing at Sayre, county of Bradford, State of Pennsylvania, have invented and produced a new and original Design for Spoons for Spoon-Bait, of which the following is a specification, reference being had to the accompanying drawings, in which—

- o Figure 1 is a face view of the spoon. Fig. 2 is an edge view thereof.
- 5 The leading feature of my design consists in a spoon or flies for a spoon-bait which is of substantially the form of an isosceles triangle, the base or longest side of which constitutes one edge of said spoon, one short side constitutes the opposite side thereof, and the other side constitutes the rear end thereof. This rear end is broken by a notch, creating 10 a re-entrant angle or recess, which bifurcates said end and creates two wings of unequal length, each wing having substantially parallel sides, or, perhaps, being somewhat narrower at their junction with the body of the 15 spoon than at their free or rearward extremities. The body and the short wing are curved,

so that the shorter edge of the spoon constitutes an arc of a circle. The other or long edge of the spoon is first curved upon the same arc to substantially the apex of said recess and is 30 then bent to form another arc of an intersecting circle, curving outwardly from the point of merger or intersection and being also given a slight twist upon the line of a spiral. The shorter wing is also given a like twist. Both 35 wings are rounded rearwardly. The body *b* is of substantially the form of an isosceles triangle, and by the re-entrant notch or angle one of the sides is bifurcated, creating the wings *c d*, which are of unequal length, and 40 said body and wings are curved substantially as above described.

What I claim is—

The design for a spoon-bait, substantially as herein shown and described. 45

In witness whereof I have hereunto set my hand this 26th day of May, 1894.

ELIAS OLIVER PEALER.

In presence of—

TRUMAN V. SLOAT,
F. J. KROM.
